US00D613004S

(12) **United States Design Patent**
Lin

(10) **Patent No.:** US D613,004 S
(45) **Date of Patent:** ** Mar. 30, 2010

(54) **GRIP FOR PET COMB**(75) Inventor: **Ralph Lin**, Taipei (TW)(73) Assignee: **Han Lien International Corp.**, Taipei (TW)(**) Term: **14 Years**(21) Appl. No.: **29/332,587**(22) Filed: **Feb. 20, 2009**(51) **LOC (9) Cl.** ..... **30-99**(52) **U.S. Cl.** ..... **D30/159; D4/138**(58) **Field of Classification Search** ..... **D30/158, D30/159, 199; D4/138, 132–137, 100–102, D4/122, 127, 119, 199, 129, 130, 104, 120, D4/131, 114; D8/106, 107, 83, 101, 307, D8/300, 303, 47, DIG. 3, DIG. 7, 20, 98–100, D8/DIG. 4, 61; 401/28, 6, 146, 188 R, 205–207, 401/270, 275, 276; 132/120, 121, 150, 152, 132/147, 148; 119/600, 601, 605, 606, 611–619, 119/625, 630–633; 15/50.1–50.3, 55, 57, 15/71, 77, 79.1, 104.002, 105, 106, 143.1, 15/98, 159.1, 160, 186–188, 176.4, 210.1, 15/244.1, 145; D7/395, 393, 649, 401.2, D7/682, 692, 642–652, 664, 688, 696, 691–693, D7/381; D24/133, 215, 214, 206; D34/27; D22/118; 30/340–344, 147–149, 325, 169, 30/172, 526, 50, 527, 151–162; 16/430, 16/431, 110.1, DIG. 12, DIG. 19, 421, 436, 16/DIG. 18; 81/489, 177.1; D32/51, 45, D32/35, 40, 48, 49, 42, 46, 52, 41; D21/756, 600/131; D28/48; 473/203; 74/551.9**

See application file for complete search history.

Primary Examiner—Susan Moon Lee*(74) Attorney, Agent, or Firm*—Browdy & Neimark, PLLC(57) **CLAIM**

The ornamental design for a grip for pet comb, as shown.

DESCRIPTION

FIG. 1 shows a perspective view of a grip for pet comb showing the present design;

FIG. 2 shows a front elevational view thereof;

FIG. 3 shows a rear elevational view thereof;

FIG. 4 shows a left side elevational view thereof;

FIG. 5 shows a right side elevational view thereof;

FIG. 6 shows a top plan view thereof; and,

FIG. 7 shows a bottom plan view thereof.
